(57) **CLAIM**

The ornamental design for a COVID immunoassay test device, as shown and described.

DESCRIPTION

FIG. 1 is a front perspective view of a COVID immunoassay test device according to the present design;

FIG. 2 is a rear perspective view thereof;

FIG. 3 is a top view thereof;

FIG. 4 is a bottom view thereof;

FIG. 5 is a left view thereof;

FIG. 6 is a right view thereof;

FIG. 7 is a front view thereof;

FIG. 8 is a rear view thereof;

FIG. 9 is an enlarged perspective view of area 9 circumscribed in FIG. 1;

FIG. 10 is an enlarged front view of area 10 marked in FIG. 7; and,

FIG. 11 is an enlarged front view of area 11 circumscribed in FIG. 7.

The dot dash dot broken lines depict the boundaries of the claim and form no part thereof.

1 Claim, 11 Drawing Sheets
